UNITED STATES PATENT OFFICE.

HENRY L. HASKELL, OF LUDINGTON, MICHIGAN.

FIGURE TOY.

1,026,861.

Specification of Letters Patent.

Patented May 21, 1912.

Application filed June 17, 1911. Serial No. 633,755.

To all whom it may concern:

Be it known that I, HENRY L. HASKELL, a citizen of the United States, residing at the city of Ludington, county of Mason, 5 State of Michigan, have invented certain new and useful Improvements in Figure Toys, of which the following is a specification.

This invention relates to improvements in 10 figure toys.

The main objects of this invention are to provide an improved figure toy which is attractive in appearance and quite strong and durable, and at the same time one which is 15 very economical to produce.

Further objects and objects relating to structural details will definitely appear from the detailed description to follow.

I accomplish the objects of my invention 20 by the devices and means described in the following specification.

The structure described constitutes one effective embodiment of my invention. Other embodiments would be readily devised by 25 those skilled in the art.

The invention is clearly defined and pointed out in the claims.

A structure constituting an effective and preferred embodiment of the features of my 30 invention is clearly illustrated in the accompanying drawing, forming a part of this specification, in which:

Figure 1 is a side elevation of a toy embodying the features of my invention. Fig. 35 2 is an enlarged front view of the toy appearing in Fig. 1. Fig. 3 is a detail perspective of the structure shown in Figs. 1 and 2, showing structural details thereof. Fig. 4 is a detail side elevation of a piece 40 of stock from which my improved toy is preferably made.

In the drawings, similar reference numerals refer to similar parts throughout the several views.

45 Referring to the drawings, the figure illustrated represents a dromedary, and comprises a body portion 1 and legs 2. The toy is cut from a piece of four-ply stock, in which the inner plies 3 are disposed so that the grain of the wood is vertical of the toy, or 50 longitudinal of the legs, while the outer plies 4 are disposed so that the grain is horizontal or transverse of the legs, as is clearly illustrated in Fig. 3. The outer plies 4 are 55 secured to the inner plies 3 throughout by gluing thereto. The inner surfaces of the

inner plies are secured together at the upper portions of the body only, as is illustrated in the drawing. The legs or appendicular portions of the toy are not glued together, 60 so that upon the drying and shrinking of the wood, the legs or appendicular members are curved outwardly, or spread apart, as shown in Fig. 2. The arrangement of the grain of the plies, as described, insures this, 65 as the wood shrinks crosswise of the grain, the outer plies thus drawing the inner plies outward. The figures are, in practice, cut by band saws so that a number can be produced at one time. The spreading of the 70 legs secures stability to the toy, and, further, this arrangement of the grain utilizes the greatest strength of the material employed, and the toys are very durable.

I prefer to use, and have described wood 75 stock or material for the manufacture of the toys, but desire to state that paper stock may be utilized, either in whole or in part: that is, part of the plies might be paper and part wood, or all paper stock disposed and 80 treated to produce the warping or curved effect.

It will be understood that the figure shown in the accompanying drawing is illustrative merely, and that birds or other figures, 85 as well as animals, can be readily produced.

Having thus described my invention, what I claim as new and desire to secure by Letters Patent, is:

1. A figure toy comprising body and leg portions, formed integrally of four-ply wood stock, the grain of the two inner plies being vertically disposed and the grain of the two outer plies being horizontally disposed, the outer plies being glued to their adjacent inner plies throughout, the inner plies being glued to each other only in the upper portion of said body, for the purpose specified.

2. A figure toy comprising body and leg portions, formed integrally of four-ply wood stock, the grain of the two inner plies being vertically disposed and the grain of the two outer plies being horizontally disposed, the outer plies being glued to their adjacent inner plies throughout, the inner surfaces of the inner plies being glued to each other only in part, whereby the leg portions are curved outwardly, for the purpose specified.

3. A figure comprising a body and ap-

pendicular members, formed integrally of stock having a plurality of plies, the grain of the inner plies being disposed longitudinally of the appendicular members, and the grain of the outer plies being disposed transversely thereof, the inner surfaces of the inner plies being united in the body portion only and the outer plies being united to the inner plies throughout, for the purpose specified.

4. A figure comprising body and appendicular members formed integrally of stock having a plurality of plies, the grain of the inner plies being disposed longitudinally of the appendicular members, the grain of the outer plies being disposed transversely thereof, the inner surfaces of the central plies being united in part only, whereby the appendicular members are spread apart, for the purpose specified.

5. A figure comprising a body and leg portions formed integrally of four ply material, the outer plies being secured to their adjacent inner plies throughout so that the

leg portions are two ply, the inner surfaces of the inner plies being secured to each other in part only, the outer plies and their adjacent inner plies being arranged to coact to curve the leg portions outwardly for the purpose specified.

6. A figure comprising a body and appendicular members formed integrally of material consisting of a plurality of plies, the outer plies being secured to their adjacent inner plies throughout so that each appendicular member is composed of a plurality of plies arranged to coact to curve the appendicular members outwardly, the inner plies being united in the body portions only, for the purpose specified.

In witness whereof, I have hereunto set my hand and seal in the presence of two witnesses.

HENRY L. HASKELL. [L.S.]
